UNITED STATES PATENT OFFICE.

GEORGE LOCKHART, OF TARRYTOWN, NEW YORK.

FIRE-ESCAPE.

SPECIFICATION forming part of Letters Patent No. 228,822, dated June 15, 1880.

Application filed April 20, 1880. (No model.)

To all whom it may concern:

Be it known that I, GEORGE LOCKHART, of Tarrytown, in the county of Westchester and State of New York, have made and invented 5 certain new and useful Improvements in Fire-Escapes, of which the following is a full, clear, and exact description, reference being had to the accompanying drawings, and to the letters of reference marked thereon, the same not 10 having been, to my knowledge, heretofore patented in any foreign country.

My invention has relation to that class of fire-escapes wherein ladders for the descent of occupants of the building are conveniently 15 arranged with respect to the doors or windows, and intended to be among the adjuncts of the building itself or attached thereon; and the object of the invention is to provide a simple, cheap, and effective means of escape in case 20 of fire or accident, under control of the occupants of the building or authorized persons on the exterior, affording an easy means of descent from any story, protection against accident from falling timbers and the like, and 25 when not in use protected from the damaging effects of rain and sun, and unaccessible to unauthorized persons.

To accomplish all of this the invention involves the use of a series of jointed ladders, 30 forming, when adjusted for use, a ladder-way from each story of the building, a hinged shield adapted to cover the ladders when not ready for use, a sliding guard adapted to cover the space between two consecutive shields, and to 35 be covered by the shields when not dropped down, a hinged balcony, and certain accessories, the parts being combined and relatively arranged in manner hereinafter first fully described, and then pointed out in the claims.

40 In the drawings, Figure 1 is a front elevation of a fire-escape constructed in accordance with my improvements. Fig. 2 is a side elevation, and Fig. 3 a vertical section, the ladders in each of these figures being closed up 45 and the apparatus represented in its ordinary position upon a building. Fig. 4 is an elevation of one side of the apparatus shown in Figs. 1, 2, and 3, the ladders and the guards, shields, and balconies being represented as 50 dropped down into position for use. Fig. 5 is

a vertical central section of the apparatus in position as indicated in Fig. 4. Fig. 6 is an elevation and partial section of one section of the apparatus, showing the shield as closed, while the movable ladder is still down, so as 55 to bring the projections on the guard over the top of the movable ladder, in order that the ladder and guard may be simultaneously returned to their proper places when the apparatus is being closed. Fig. 7 is a perspective 60 view, indicating the manner in which the balcony is supported upon the window-sill when the balcony is in position for use.

In all the figures like letters of reference, wherever they occur, indicate corresponding 65 parts.

The system herein shown is applicable to a building of any number of stories; but in order to illustrate the principles of my invention it has been deemed necessary to show 70 only two sections of the improved escape, other sections being added as the number of stories is increased, or only one section used at pleasure.

In each section of the escape I employ a stationary ladder, as at A, secured in any suitable permanent or semi-permanent manner to the side of the building, and near the windows or other openings, where they will be 75 convenient of access.

Over the ladder A is mounted a second movable ladder, B, running in guides upon A, or otherwise arranged in connection therewith, so that it will slide up and down easily without danger of lateral displacement. This 85 ladder B is intended to reach from the bottom of one stationary ladder, A, to the top of the next one below, as indicated in the sectional view, Fig. 5. It is provided with a hoisting chain or cable, b, running over a pulley, c, 90 above, preferably on the top rung of ladder A, and connected with a shaft, d, upon which a wrench, e, may be applied to wind the ladder up, when desired to close up the apertures.

95 Instead of a single hoisting-chain at the center of the ladder, it may be found advantageous to employ two chains, and locate one at each side, so as to be out of the way of the feet and hands of the persons descending.

The outer shield, C, covers both ladders when in place, and it is hinged to the side strips of ladder A by two or more arms, *ff*, which, when the shield is lowered, cause it to 5 assume a position far enough from the ladder to allow a person to move up and down on the ladder with sufficient freedom.

Suppose the movable ladder to be down. Then, to close the apparatus they are wound 10 up by their respective winding-chains, one at a time, until at their proper places. The shields C are first elevated by suitable chains or cables, *g*, and thus swung into their places upon the arms *f*, where they are caught by the 15 hooks *h*, properly pivoted upon the sides of ladder A, or at any convenient point, and held closed. The hooks *i* upon ladders B catch over the tops of shields C and hold the ladders up. The hook *i* on ladder B must be in 20 the form of a spring or equivalent, so that when the ladder reaches its proper position it must be thrown out over the top of the shield upon which the ladder is supported. Being up, it is plain that when hooks *h* are detached or 25 moved the shields will drop down and the movable ladders fall to their extended position by their own weight. The hooks *h*, upon the lower sections of the escape, are each provided with an arm, *h'*, as shown in Figs. 1 and 4, 30 extending in the path of the falling ladder above, so that in order to drop all the movable ladders it is only necessary to detach the uppermost hook, and each falling ladder of the system will release the shields and corre- 35 sponding ladders of each of the sections below by striking upon the arm *h'*, and thus tripping or releasing hook *h*. The cord connected with the uppermost hook, *h*, should be located inside the building, within convenient 40 access of the occupants, and, if carried to the exterior, protected in any suitable manner, as by a lock, so that it is only accessible to authorized persons who may be in possession of the key. It might be well to make this releas- 45 ing-cord of such material as to be easily burned, and to expose it upon the interior in such manner that any fire in its neighborhood will burn it, and thus automatically release the ladders and allow the apparatus to assume a position 50 ready for use.

The shields C serve not only to protect the working parts of the apparatus when not in use, but they afford a cover for the escaping persons, protecting them from falling brands, 55 falling timbers, &c. They also, in a great measure, add to the security of the apparatus, in that persons using the ladders are by them confined to a comparatively narrow space, and are thus less liable to dizziness or to lose their hold or 60 footing, as sometimes happens in the old forms of uncovered ladders.

The shields may, of course, be utilized for ornamental effect upon the building, adding to the appearance thereof rather than detract- 65 ing from it, as in most forms, and especially may they be utilized for sign-spaces or adver-

tising-spaces, as on stores and the like. With in each shield C is a second metallic guard, D, movable like the ladder B, and intended to reach from one section to the other, covering 70 ladder B when down. This guard D may be made of light metal, and it has any form of slight projection *w* sufficient to connect its top with the top of the movable ladder, so that when the ladder is elevated the guard will also 75 be elevated. The guard moves in suitable guides upon the outer shield, and when the latter is closed up it carries the guard with it, as indicated in Fig. 6, so that the projection *w* is brought over the ladder B. For this rea- 80 son, in closing up the apparatus the shield is closed first, as previously explained.

The guard is prevented from falling too far by stop *w'* on the guard, which strikes the top of the guide *g'*.

On each shield C is hinged a balcony-platform, E, with upright F, hinged to the platform, and horizontal bars G G, all so arranged that it will fold up and form, when in place, a portion of the side wall of the shield. This 90 platform might be connected in any suitable way with the movable ladder, so that when the latter is elevated the platform would be folded into place; but the closing up of the apparatus is not a feature of so much impor- 95 tance as is the ready ease and sure means of dropping it down into position for use. The closing might be accomplished in any one of a variety of ways. As the shield falls the balcony automatically assumes its proper place 100 in front of the window or other passage. When down the bottom of the balcony rests upon the projecting window-sill, as plainly indicated in Fig. 7, which sill affords a firm support for the balcony and any weight likely to be placed 105 thereon.

An alarm-bell, H, is arranged to be operated by the lower ladder for awakening the occupants of the house, giving the alarm of fire, and especially to indicate that the fire-escape has 110 been moved, so that in case the ladders be dropped by any unauthorized person attention will be directed thereto. The means of ringing the bell is very simple: a bent arm, K, carrying the striker, is pressed by spring *k* 115 against the rungs of the movable ladder, so that as each rung passes the arm K the bell is struck once. As the ladder is made to descend very rapidly the ringing of the bell will be somewhat peculiar, and readily recognizable as an alarm to persons within the building. The bell should, of course, be concealed or protected. It might be located under the ladder B or elsewhere, as convenience might suggest.

Having now fully described my invention, what I claim as new, and desire to secure by Letters Patent, is—

1. In a fire-escape of the character herein specified, the stationary ladder, a movable ladder mounted thereover, a hinged shield covering the stationary ladder, and a depressible

- guard adapted to cover the depressed ladder, these parts combined and arranged to operate substantially as shown and described. 25
2. In combination with a hinged shield for the ladders of a fire-escape, the locking-hook, adapted to be tripped and to release the shield, substantially in the manner and for the purposes set forth. 30
3. The combination, with the movable ladder, of the sliding guard connected therewith, and made to rise and fall with the ladder, substantially as shown and described. 35
4. In a fire-escape, the combination of the independent sections thereof, each having a stationary ladder and a movable ladder, outer shield, and movable guards, the movable ladder of the upper section being arranged to release the shield, ladder, and guards of the lower section, substantially as shown and described. 40
5. The combination of the hinged shield for the ladders and the folding balcony, connected therewith and adapted to drop down into place before the window or other aperture, substantially as shown and described. 45
6. In a fire-escape having one or more movable ladders, the combination, with the movable ladder, of the alarm-bell, operated by a bent spring-actuated arm which receives its motion from contact of the rungs of the falling ladder, substantially as and for the purposes explained. 50
7. The depressible ladder, provided with a hook adapted to engage with the top of the hinged shield and to be held in its closed position by said shield, substantially as shown and described. 55

In testimony that I claim the foregoing I have hereunto set my hand in the presence of two witnesses.

GEORGE LOCKHART.

Witnesses:

WORTH OSGOOD,
ARTHUR M. PIERCE.
